United States Patent Office

Des. 196,955
Patented Nov. 19, 1963

196,955

LUGGAGE CASE

Kendrich T. Parsell, Evanston, Ill., assignor to Stein Bros.
Manufacturing Company, a corporation of Illinois

Filed Apr. 22, 1963, Ser. No. 74,537

Term of patent 14 years

(Cl. D87—5)

FIGURE 1 is a perspective view of a luggage case showing my new design, the one end and opposite side not seen being substantially identical to the end and side shown; and

I claim:

The ornamental design for a luggage case, substantially as shown and described.
